UNITED STATES PATENT OFFICE.

JOHN H. SMYTH, OF BRIDGEBURG, ONTARIO, CANADA.

PROPELLER FOR AIRCRAFT.

1,243,885.

Specification of Letters Patent. Patented Oct. 23, 1917.

Application filed July 27, 1916. Serial No. 111,651.

To all whom it may concern:

Be it known that I, JOHN H. SMYTH, of the village of Bridgeburg, in the county of Welland and Province of Ontario, Dominion of Canada, have invented certain new and useful Improvements in Propellers for Aircraft; and I hereby declare that the following is a full, clear, and exact description of the same.

10 A propeller for air craft, as now constructed, is provided with a set of single blades, arranged at an angle incident to a plane perpendicular to the axis of revolution, for producing when revolved, motion 15 or pressure in the direction of such axis, the angle of incidence governing the driving factor of the propeller; that is to say, the greater the angle of incidence up to a critical point, the greater the driving force, 20 and vice versa. The driving force in the case of a set of single blades, however, is out of all proportion to the rotational speed, in comparison to the power which would be derived if a set of double blades were employed and the components set at different 25 angles of incidence such as to produce the maximum leverage upon the blades without creating a region of rarefaction.

The object of this invention, therefore, is 30 to obtain an increase of driving power at the usual rotational speed, and this object is attained by providing the propeller with a set of double blades arranged at such angles of incidence as to produce a greater 35 leverage, and consequently more power at the same rotational speed, or the same power at a lower rotational speed, than in the case of a propeller having a set of single blades, the components of the double blades being 40 arranged so that one, which may be termed the "leading blade", cleaves the air at an angle of incidence such as to produce the maximum of leverage upon the blade and utilize the entire volume of air encountered, 45 without setting up a region of rarefaction, and the other, which may be termed the "following blade", set at a different angle of incidence, such as to act upon the current of air generated by the leading blade, 50 produces the maximum leverage and utilizes the entire volume of air encountered, without setting up a region of rarefaction.

In the drawings:—

Figure 1, is a perspective view of the

propeller showing the arrangement of the 55 blades;

Fig. 2, is a detail view of one of the leading blades;

Fig. 3, is a perspective view of one of the 60 following blades;

Fig. 4, is a detail view of the hub shown in Fig. 1;

Fig. 5, is a perspective view of a modification of the hub shown in the preceding 65 views;

Fig. 6, is a cross sectional view showing the angles of incidence of the leading and following blades.

Like characters of reference refer to like parts throughout the specification and drawings.

The essential feature of the invention is not so much the shape of the blades, as almost any type can be used, but it is the principle of arranging the blades in pairs, 75 with the components of each pair at different angles of incidence to the plane of revolution, and one component in advance of the other in the circle of rotation.

In carrying out this principle, I have 80 shown in the drawings, and hereinafter described, a convenient type of propeller, consisting of sets of double blades, *a*, *b*, and *a'*, *b'*, respectively, the blades *a*, *a'* being hereinafter termed the "leading blades", 85 and the blades *b*, *b'*, the "following blades", the leading blades being at relatively small angles of incidence and the following blades at relatively greater angles of incidence, to the plane of the revolution of the propeller. 90

These blades may be integrally formed from a unitary casting or forging, or cut from a block of metal or wood, as is most suitable for the purposes for which the propeller is intended, but a convenient method 95 of constructing the propeller is to provide a hub *c*, such as is shown in Figs. 1 and 4 of the drawings, or a hub *d* similar to that shown in Fig. 5, or any modification of these constructions within the scope of the appended claims, and to bolt or otherwise fasten the leading and following blades to it at appropriate angles of incidence to the plane of revolution with the leading blade in advance of the following blade in the 100 circle of rotation.

In Figs. 1, 4 and 5, the hub is shown to be substantially rectangular in cross section,

with two diametral extensions or hub members c' disposed lengthwise of the blades. This hub construction provides shoulders c^3 to engage with corresponding shoulders e , 5 in the inner faces of the arms e' of the blades, the inner face of each arm e' abutting against the adjacent side of its respective hub member c' and being formed with an elongation e'' overlapping its respective 10 part of the hub and abutting against the end of the elongation of the arm of the other blade on the same side of the hub.

As shown in Fig. 1, a leading blade and a following blade are located on each side of 15 the hub, for instance, the leading blade a and the following blade b are located on one side of the hub, and the leading blade a' and the following blade b' are located on the other side, with the leading blades in 20 advance of the following blades in the circle of rotation, and the inner faces of the arms of each of the blades engaging the corresponding faces of the hub member c' and the shoulders e of the arms e' engaging the 25 shoulders c^3 .

Appropriate means are employed to secure the blades to the hub, such means preferably consisting of passing through the leading blade a , hub, and following blade b' , 30 a bolt or set of bolts f , and passing through the leading blade a' , hub, and following blade b , a similar bolt or set of bolts f' , these bolts rigidly fastening the leading and following blades to the hub.

35 As shown in Fig. 1, the hub is provided with plates g located at opposite sides of the hub to engage the arms of the leading and following blades, these plates being securely bolted or screwed to the hub, for the 40 purpose of preventing the lateral displacement of the assembled parts, and as shown in Fig. 5, the top and bottom of the hub are formed with overhanging flanges h , the flanges engaging the adjacent surfaces of 45 the arms for the same purpose as the plates g , and as shown in Fig. 3, the leading blades are formed with shoulders a'' to engage the ends of the hub members c' when the parts are assembled.

50 This arrangement provides for a rigid assembly of the parts and a substantial bearing for the arms of the blades upon the hub, so that when the arms and the hub are bolted together, the blades will be immovably held in their fixed relation, to resist 55 the rotational torsion.

As shown in Fig. 1, the leading blades a , a' , which are arranged in advance of, the following blades b , b' , respectively, in the 60 circle of rotation are at a relatively small angle of incidence to the plane of the rotation of the propeller, and spaced sufficiently from the following blades to permit of the air disturbed by the following blades clearing 65 the propeller.

The following blades b , b' , as shown in Figs. 1 and 6, are at a relatively great angle of incidence to the plane of the rotation of the propeller, and overhang the front and rear faces of the leading blades a , a' . 70

That part b^4 of each following blade, overhanging the front face a^4 of each leading blade, displaces an amount of air in proportion to the amount of lead it may have. 75

That part b^5 of each following blade, overhanging the rear face of each leading blade, acts upon the air displaced by the front overhang b^4 and the leading blade in proportion to the area of the overhang. 80

During the rotation of the propeller, the leading blades, cleaving the air, effect a displacement and set up an air current or motion in the direction of the rear overhang b^5 of the following blades, their angles of 85 incidence being such that a maximum leverage is obtained under the conditions previously stated.

The front overhang b^4 of each following blade, cleaving the air, effects a displacement toward the rear. The air so displaced by the front overhang b^4 passes across the face of the following blade to the rear edge, the separation between the leading and following blades being provided for that purpose. Consequently the following blades, by cleaving the air, and by utilizing the air thus displaced, and because of their greater angle of incidence, produce a maximum of leverage. 90

By this construction, the driving power is greater than that of a single blade at the same rotational speed; consequently, it is possible by the use of a propeller having a set of double blades, to derive a greater 105 driving power at the same rotational speed, or the same driving power at a lower rotational speed, than in the case of a propeller with a set of single blades.

Having thus fully described the nature 110 of my invention, what I claim as new and desire to secure by Letters Patent, is:—

1. A propeller comprising a double propeller blade, consisting of two components at different angles of incidence to the plane 115 of revolution, with one component overhanging the other and separated therefrom, whereby the air displaced by the components may pass through the separation.

2. A propeller comprising propeller 120 blades arranged in pairs with the components of each pair at different angles of incidence to the plane of revolution, and one component in advance of the other in the circle of rotation, the following component 125 overhanging the leading component and separated therefrom, whereby the air displaced by the components may pass through the separation.

3. A propeller comprising propeller 130

- blades arranged in pairs with the components of each pair at different angles of incidence to the plane of revolution, and one component in advance of the other in the circle of rotation, the following component overhanging the front and rear faces of the leading component, and separated therefrom, whereby the air displaced by the components may pass through the separation.
- 10 4. A propeller comprising a propeller blade, consisting of two components, one of which is placed in advance of the other in the circle of rotation, the two components being at different angles of incidence and
- 15 one of the components overhanging the front and rear faces of the other, there being a separation between them whereby the

air displaced by the components may pass through the separation.

5. A propeller comprising a set of double propeller blades, each double blade consisting of two components, one of which is in advance of the other in the circle of rotation, and at a different angle of incidence thereto, one of the components overhanging the front and rear faces of the other, there being a separation between them whereby the air displaced by them during their rotation can pass therethrough.

Buffalo, July 10th, 1916.

JOHN H. SMYTH.
